UNITED STATES PATENT OFFICE.

EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

LOOM.

Application filed September 23, 1924. Serial No. 739,327.

To all whom it may concern:

Be it known that I, EDWARD A. CUNNIFF, a citizen of the United States, residing at Waltham, county of Middlesex and State 5 of Massachusetts, have invented an Improvement in Looms, of which the following description, in connection with the accompanying drawings, is a specification, like characters on the drawings representing like parts.

This invention relates to looms, and more particularly to harness controlling mechanism.

In the production of certain characters of 15 novelty cloth it is desirable to weave a portion of the cloth with a pick of filling in each shed, and at intervals to weave the cloth with a plurality of picks of filling in a single shed, the filling in each instance, 20 however, being beaten up by the lay. The novelty cloth thus produced will have zones of plain or similar weave separated at intervals by zones wherein a plurality of the filling is contained in each shed, thereby 25 producing a striped effect.

In accordance with the present invention the warp threads are manipulated by at least two harnesses which are operated by means for the production of sheds for the 30 filling, and at intervals the shed forming movement of the harnesses is interrupted with the shed open, whereby the plurality of picks of filling may be placed in the single shed. During the introduction of the 35 plurality of picks of filling into the single open shed it is desirable that the filling threads shall be bound at the opposite edges of the cloth for the production of selvages, and another important feature of the present 40 invention therefore consists in a selvage forming mechanism operable during the introduction of the plurality of picks of filling in the open shed to bind or form a selvage with such filling threads.

45 More specifically stated, the present invention contemplates that the harnesses of a pair shall be alternately raised and lowered for the production of single sheds and that at intervals means shall operate automatically to interrupt the operation of the harnesses with the shed open and on completion of the desired number of filling threads into the open shed that the harness controlling mechanism shall effect the operative condition of the harnesses.

While the invention will be hereinafter described in connection with a single pair of harnesses, the advantages of the invention may be utilized in connection with more than a single pair.

60 The invention, new combination of parts and novel features will best be made clear from the following description and the accompanying drawings of one good practical form of the invention.

65 In the drawings:

Fig. 1 is a perspective view looking from the front and side of the loom and showing the invention associated with a single pair of harnesses;

70 Fig. 2 is an edge view of the novelty cloth that is produced by the present invention;

Fig. 3 is a side elevation of the loom, some of the parts being shown in section; and

75 Fig. 4 is an enlarged detail showing the harness controlling lock.

The loom with which the present invention is associated is provided with the usual warp beam, take-up mechanism, lay, and pick mechanism, all of which operate as 80 usual in sequence in the production of cloth, and associated with such parts are the features of the present invention.

The loom frame 1 may be of usual construction, and at the rear portion thereof has 85 a support 2 for a warp beam 3. The warp threads *a* pass from the warp beam over the whip roll 4 which may be of usual construction and thence the warp threads pass forwardly through the harnesses, the 90 dents of the reed to the fell of the cloth, and the cloth as it is woven is taken up by the usual train of take-up mechanism 5. Since the take-up mechanism may be of any usual construction, it is not herein specifically 95 shown and described, the condition being such that on each cycle of cloth production, the cloth will be taken up by the take-up mechanism.

100 Pivotedly mounted at the lower portion of the loom frame at 6 are the lay swords 7 carrying the usual lay 8 and reed 9, Fig. 3, as shown, and the lay is given its beat-up movement through the pitman 10 deriving its movement from the crank shaft 11. On 105 each cycle of loom operation, as, for instance, when the lay is in its back or nearly back position, as shown, the filling thread is introduced to the shed and, in the present instance, such introduction of the filling 110

thread is effected by means of a single shuttle 12 which may be picked through the shed as usual.

- Between the whip roll 4 and the lay 8 are 5 two harnesses 13 and 14, each of which comprises a frame carrying heddles, such as 15, for raising and lowering the warp threads in the formation of the sheds. The two harnesses 13 and 14 are joined together by harness connectors 16, herein shown as straps, which pass over and may be secured to the rocker 17 preferably formed as a shaft supported at each end in bearings 18 extending from the loom arch 19. The connectors 16 10 are preferably secured to the rocker or rock shaft 17, as at 20, so that upon the operation of the harnesses in the formation of a shed, the rocker or rock shaft will be given a rocking movement.
- 20 One of the harnesses is connected to a harness operating means and, as shown, such means consists of a treadle or lever 21 pivotally mounted at 22 at the rear of the loom, and having a strap or connection 23 25 extending to a yoke 24 which is itself connected to the harness 14 by the links 25. The other harness 13 of the pair is normally under the influence of the springs 26 tending to lower the harness 13 and, perforce, 30 raise the associated harness 14.

Extending between the sides of the loom is the lower or cam shaft 27 on which is mounted a cam 28 which operates upon a roll 29 to lower the harness 14, and consequently 35 raise the associated harness 13, the construction being such that upon rotation of the under or cam shaft, when the parts are free to operate, the two harnesses 13 and 14 will be alternately raised and lowered during each cycle of loom operation in the formation of sheds for the introduction of a weft or filling thread, it being understood that during the cycles of loom operation the under or cam shaft, the lay, the 40 picking mechanism and the take-up mechanism continue to function.

Secured to the rocker or rock shaft 17 for rocking movement therewith is the arm 30 having a turned end portion 31 and during 45 the operation of the rocker or rock shaft 17 the arm 30 swings through its arc of movement defined by the amplitude of rocking movement of the rocker or rock shaft.

Mounted upon the loom frame, as shown, 50 preferably secured to the loom arch are two bearings 32, in which is rotatively mounted the controller shaft 33 which has a worm gear 34 secured thereto and driven by a worm 35 on a shaft 36, Fig. 1, which may be driven from the under or cam shaft 27. In the present instance the shaft 36 is supported in a bearing 37 extending from one of the uprights 38 which constitutes a support for the loom arch, and at its lower end the shaft 36 carries a bevelled gear 39 which

is operatively connected to a similarly bevelled gear 40 on the under or cam shaft 27, the construction being such that during the rotation of the under or cam shaft 27 the controller shaft 33 will continue to operate or rotate, although at a somewhat slower speed.

The controller shaft 33 has connected thereto a controller for controlling the periods of activity and inactivity of the harnesses. In the present instance the controller comprises a rotating member 41 secured to the controller shaft 33 and carrying a controlling member 42, which, as the controller 41 slowly rotates, as hereinbefore described, will eventually pass in front of the projection 31 on the arm 30 and interrupt the movement of the rocker or rock shaft 17. The parts are so related that the controller member 42 comes into operative position to arrest the movement of the arm 30 when the lever 21 has been depressed by its cooperating member 28 on the under or cam shaft, and means are provided to thereupon lock the lever 21 in its lowered position for a period of time with the shed open. The duration of the open shed will therefore depend upon the extent of the surface of the controller member 42, and by varying the width of such controller member the periods of inactivity of the harnesses may be made longer or shorter, as desired, for the introduction of any predetermined number of weft or filling threads into the open shed. One convenient way of varying the duration of the open shed and perforce vary the number of weft or filling threads introduced therein is to form the controller member 42 as a detachable element which may be detachably secured to the controller 41 by means, such as one or more bolts 43.

By making the worm gear 34 interchangeable or of different sizes, the speed of the rotation of the controller shaft 33 may be varied, thereby varying the extent of the plain portions woven into the cloth. In other words, should the shaft 33 be rotated at a predetermined speed, the harnesses will continue to form successive single sheds for the successive introduction of single picks of filling, until the controller member 42 interrupts the operation of the harness operating mechanism, and should the shaft 33 be rotated at a different speed, the number of single picks of filling successively introduced into the successive sheds will of course vary. Consequently the cloth may have any predetermined number of plain woven portions separated by any predetermined number of filling threads placed in the open shed and consequently the cloth will have different striped effects.

The present invention contemplates that when the shed is to remain open for the insertion of a plurality of successive picks of

filling in the same shed, the harness operating mechanism shall be locked, and to this end there is mounted near the under portion of the loom, preferably on the supporting floor or a member secured to the loom frame, a bracket 44 on which is pivotally mounted at 45 a locking arm 46, the end portion 47 of which is adapted to project above a plate 48 secured to the lever 21, in order to lock the lever 21 in its downward or in the open shed position. Secured to the locking arm 46 is a finger 49 normally under the influence of a spring 50 tending to throw the locking lever 46 into its locking position. Also secured to the finger 49 at 51 is a strap or like connection 52 which extends upwardly to and about a projection or cam 53 secured to the rocker or rock shaft 17, the construction being such that when the finger 30 is held by the controller member 42 from oscillating, the rocker or rock shaft 17 will likewise be interrupted in its movements and the connection 52 will be slackened so that the spring 50 may act to throw the locking end 47 of the locking member 46 into locking engagement with the lever 21, and the parts will remain in this position with the shed open so long as the controller member 42 acts upon the end 31 of the arm 30. When, however, the controlling member 42 is moved past the end 31 of the arm 30, the latter will be free, with the result that the springs 26 acting through the harness 18 will turn the rocker or shaft 17 sufficiently to draw upward on the connection 52 and disengage the lock from the lever 21, whereupon the harnesses will be operated alternately through the lever 21 and the springs 26 in the formation of successive sheds for single shots of filling.

During the continuance of the open shed for the introduction of a plurality of picks of filling, the present invention provides that a selvage may be formed at the edges 45 of the cloth, since otherwise the picks of filling might not remain in their proper location at the selvage line.

In the present instance, a selvage heddle 54 is located at each side of the cloth and has an eye 55 through which passes one of the warp threads, as *b*, at the edge of the cloth. The heddle 54 is normally depressed by a spring 56, one end of which is connected to the heddle 54 at 57 and the other end 50 to a fixed point, as at 58. Extending upwardly from each of the heddles 54 is a strap 59 which passes over a loose pulley 60 mounted on a bracket 61 secured to the loom arch at each side of the loom. From the pulley 60 the strap 59 passes downwardly and is secured at 62 to an arm 63 which may be appropriately raised and lowered by means of a cam 64 on the under or cam shaft 27. In the present instance, the arm 65 60 is shown as secured to the shoe 65 of the

cam follower 66, and the spring 67 normally acts through the arm 63 to hold the shoe of the cam follower on its actuating cam 64. The construction just described is shown at one side of the loom in Fig. 1, but it is to 70 be understood that this, or a similar mechanism, is to be employed at the opposite side of the loom for operating the selvage threads *b* to engage the loop of filling at each side of the loom to form the cloth selvage. 75

The novelty cloth shown by Fig. 2 comprises sections 68 of the plain woven cloth, wherein a single pick of filling is contained 80 in each shed, and other sections 69, wherein the shed has a plurality of picks of filling which form a contrasting appearance and produce a striped or novelty effect.

As hereinbefore pointed out, the number of picks of filling in the sections 68 may be 85 varied by change or variation in the worm gear 34, and the number of picks of filling in a single shed, as at 69, may be varied by changing the size or contour of the controlling member 42. 90

During weaving with the successive shed formations on recurring cycles of loom operation, the single shuttle preferably employed to lay the filling in the shed, will introduce a single pick of filling. When the controller 41 brings the controller member 42 in operative relation with the rocker arm 30, the operation of the harness operating mechanism will be suspended with the shed open and the lever 21 depressed, and the parts will be held in this position by the lock for the introduction of a plurality of picks of filling in the open shed. During this time the other parts of the loom continue in operation and each filling thread 100 as it is introduced into the shed is moved forwardly or "beaten up," both in the single and open shed, and when the desired number of picks of filling have been introduced in the continuously open shed and 105 tied at the cloth edges to form a selvage, the controller member 42 will pass out of engagement with the rocker arm 30 and the loom will continue to run pick and pick until the controller member 42 again engages 110 the rocker arm to suspend the harness movements with the shed open. 115

What is claimed is:

1. In a loom for weaving novelty cloth, the combination of the harnesses for controlling the warp threads, means for operating the harnesses in forming the shed, locking means for automatically locking the harness operating means at intervals with the shed open while the loom continues to run for the introduction of a plurality of picks of filling in the same shed, automatically acting lock tripping means to trip the lock at intervals, and selvage forming means for producing a selvage along the edge of the cloth 120
2. In a loom for weaving novelty cloth, the combination of the harnesses for controlling the warp threads, means for operating the harnesses in forming the shed, locking means for automatically locking the harness operating means at intervals with the shed open while the loom continues to run for the introduction of a plurality of picks of filling in the same shed, automatically acting lock tripping means to trip the lock at intervals, and selvage forming means for producing a selvage along the edge of the cloth 125
3. In a loom for weaving novelty cloth, the combination of the harnesses for controlling the warp threads, means for operating the harnesses in forming the shed, locking means for automatically locking the harness operating means at intervals with the shed open while the loom continues to run for the introduction of a plurality of picks of filling in the same shed, automatically acting lock tripping means to trip the lock at intervals, and selvage forming means for producing a selvage along the edge of the cloth 130

during the introduction of a plurality of picks of filling in the open shed.

2. In a loom of the character described, the combination of the harnesses, means for operating the harnesses in the formation of the shed, means for introducing a pick of filling in the shed, a lock for locking the harness operating means at intervals with the shed open for the introduction of a succession of picks of filling in the same shed, a trip for tripping the lock after a predetermined number of picks have been laid in the open shed, and means for forming a selvage during the introduction of the plurality of picks of filling in the open shed.

3. In a loom, the combination of the harnesses for controlling the warp threads in the shed formation, means for operating the harnesses, a lock for locking the harness operating means with the shed open during the introduction of a plurality of picks of filling in the same shed, the lay for beating up the successive picks of filling, and means for tripping the lock at intervals for the formation of successive sheds and the introduction of picks of filling in each shed.

4. In a loom, the combination of the harnesses for controlling the warp threads in the formation of the shed, a single shuttle for introducing successive picks of filling, the lay for beating up the successive picks of filling, and means for automatically locking the harnesses in position with the shed open at intervals for the introduction of a plurality of picks of filling in the same shed and then freeing the harnesses for the formation of successive sheds for the introduction of single picks of filling for each shed.

5. In a loom, the combination of the harnesses for controlling the warp threads in the formation of the shed, a single shuttle for introducing successive picks of filling, the lay for beating up the successive picks of filling, means for automatically locking the harnesses in position with the shed open at intervals for the introduction of a plurality of picks of filling in the same shed and then freeing the harnesses for the formation of successive sheds for the introduction of single picks of filling for each shed, and means for varying the intervals of operating the locking means.

6. In a loom, the combination of the harnesses for controlling the warp threads in the formation of the shed, a single shuttle for introducing successive picks of filling, the lay for beating up the successive picks of filling, means for automatically locking the harnesses in position with the shed open at intervals for the introduction of a plurality of picks of filling in the same shed and then freeing the harnesses for the formation of successive sheds for the introduction

of single picks of filling for each shed, and means for forming a selvage during the continuance of the open shed and introduction of successive picks of filling in the same shed.

7. In a loom, the combination of two harnesses for controlling the formation of the shed, a connection between the two harnesses, a cam actuated lever for operating the two harnesses, a lock for locking the lever to suspend the successive shed formations with the shed open for the introduction of a plurality of picks of filling in the same open shed, and means for automatically controlling the lock during the operation of the loom.

8. In a loom, the combination of two connected harnesses for forming the shed, a cam actuated lever for operating the harnesses, a lock for suspending the operation of the lever with the shed open, and a controller for automatically operating the lock at intervals that the harnesses may form successive sheds for the introduction of a pick of filling and then maintain the shed open at intervals for the introduction of a plurality of picks in the same open shed.

9. In a loom, the combination of two connected harnesses for forming the shed, a cam actuated lever for operating the harnesses, a lock for suspending the operation of the lever with the shed open, a controller for automatically operating the lock at intervals that the harnesses may form successive sheds for the introduction of a pick of filling and then maintain the shed open at intervals for the introduction of a plurality of picks in the same open shed, and means for forming a selvage during the introduction of the plurality of picks in the open shed.

10. In a loom, the combination of the harnesses, a cam actuated lever for operating the harnesses in the formation of the shed, a lock for said lever to suspend the operation of the harnesses at intervals with the shed open, and a controller for automatically causing the lock to suspend the operation of said lever for a predetermined interval and then free the lever that an open shed may be maintained for an interval during the loom operation for the introduction of a plurality of picks in the same open shed.

11. In a loom, the combination of the harnesses, a cam actuated lever for operating the harnesses in the formation of the shed, a lock for said lever to suspend the operation of the harnesses at intervals with the shed open, a controller for automatically causing the lock to suspend the operation of said lever for a predetermined interval and then free the lever that an open shed may be maintained for an interval during the loom operation for the introduction of a

plurality of picks in the same open shed, and means for varying the periods of duration of the open shed.

12. In a loom, the combination of two harnesses, harness connectors between them, a cam actuated lever for operating the harnesses, a rock shaft actuated by movement of the harnesses in forming the shed, a lock for suspending the shed forming movement of the harnesses, means associated with the rock shaft and connected to the lock, and a controller for interrupting the movement of the rock shaft at intervals to cause the lock to suspend the harness movements with the shed open for the introduction of a plurality of picks in the same shed.

13. In a loom, the combination of two harnesses, harness connectors between them, a cam actuated lever for operating the harnesses, a rock shaft actuated by movement of the harnesses in forming the shed, a lock for suspending the shed forming movement of the harnesses, means associated with the rock shaft and connected to the lock, a controller for interrupting the movement of the rock shaft at intervals to cause the lock to suspend the harness movements with the shed open for the introduction of a plurality of picks in the same shed, and means for varying the duration of the open shed.

14. In a loom, the combination of two harnesses, connectors between the two harnesses, a cam actuated lever connected to one

of the harnesses, springs connected to the other harness, an overhead rocker about which the harness connectors pass, a lock for holding the cam actuated lever inoperative for a plurality of picks with the shed open, and a lock controller acting through the overhead rocker for automatically rendering the lock operative at intervals during weaving.

15. In a loom, the combination of a rocker, harnesses connected to the rocker for movement in opposite directions, means for operating the harnesses, a rocker controller for suspending the rocking movement of the rocker at intervals with the shed open for a plurality of picks, and a lock rendered effective through the rocker for interrupting effective operation of the harness operating means.

16. In a loom, the combination of a rocker, harnesses connected to the rocker for movement in opposite directions, means for operating the harnesses, a rocker controller for suspending the rocking movement of the rocker at intervals with the shed open for a plurality of picks, a lock rendered effective through the rocker for interrupting effective operation of the harness operating means, and means for varying the duration of the inoperative condition of the harness operating means.

In testimony whereof, I have signed my name to this specification.

EDWARD A. CUNNIF. 65
